(57) **CLAIM**

The ornamental design for a deck frame assembly as shown and described.

DESCRIPTION

FIG. 1 is a front, top, right perspective view of a deck frame assembly showing our new design.

FIG. 2 is a right side view thereof.

FIG. 3 is a left side view thereof.

FIG. 4 is a front view thereof.

FIG. 5 is a back view thereof.

FIG. 6 is a top view thereof.

FIG. 7 is a bottom view thereof; and,

FIG. 8 is a zoomed in view of a portion thereof identified in FIG. 1.

The long-short dash lines depict boundaries of the claimed design. The even dash lines depict portions of the article forming no part of the claimed design.

The deck frame assembly is shown with symbolic break lines. The break lines and the appearance of any portion of the article between the break lines form no part of the claimed design.

1 Claim, 8 Drawing Sheets

FIG. 1.

FIG. 2.

FIG. 3.

FIG. 4.

FIG. 5.

FIG. 6.

FIG. 7.

FIG. 8.
